UNITED STATES PATENT OFFICE.

LOUIS A. HOERR, OF ST. LOUIS, MISSOURI.

DOOR-HANGER.

SPECIFICATION forming part of Letters Patent No. 645,094, dated March 13, 1900.

Application filed March 27, 1899. Serial No. 710,533. (No model.)

To all whom it may concern:

Be it known that I, LOUIS A. HOERR, a citizen of the United States, residing at St. Louis, in the State of Missouri, have invented a new 5 and useful Door-Hanger, of which the following is a specification.

My invention relates to improvements in that class of hangers for sliding doors in which the hanger is provided with a sheave running 10 in a sheave-holder; and my improvements are particularly useful in connection with freight-car doors.

The chief objects of my improvements are, first, to diminish friction while the door is being started in either direction until it has an 15 opportunity to gather momentum; second, to provide improved means for introducing the sheave into its holder and for removing it therefrom; third, to provide means for holding the sheave in place when one of its trunnions is broken; fourth, to provide means for preventing the escape of the sheave when 20 both its trunnions break; and, fifth, to provide means for supporting the hanger when its 25 sheave is so broken as to be useless. I attain these objects by the mechanism illustrated in the accompanying drawings, in which—

Figure I is a side elevation of a portion of a car having a door supported by a pair of 30 my improved door-hangers. Fig. II is a vertical central section. Fig. III is an isometric projection of my improved hanger looking from in front, and Fig. IV is a similar view looking from the rear.

Similar letters refer to similar parts throughout the several views.

A represents the side of a freight-car.

B is a car-door; C, a door-track resting upon a supporting-strip c, attached to the side of 40 the car in the usual way, and D D are hangers, by means of which the door B is suspended from track C.

The track C is preferably in the shape of an inverted T in cross-section and may be 45 formed of a strip of T-iron arranged with its web c' projecting upward and its tread c² projecting laterally on each side of the web, substantially as shown in the drawings.

Each hanger is composed of a housing D', 50 having a depending arm D² and a sheave D³. The housing contains an opening d for the sheave, which opening is preferably, but not

necessarily, rectangular in cross-section, and its sides d' and d² are preferably, but not necessarily, substantially vertical and parallel. 55 Its ends d³ are preferably so closed as to prevent the escape of the sheave, and preferably by parallel vertical walls, as shown. The depending arm D² is preferably pierced by holes d⁴, through which screws or bolts d⁵ preferably pass and fasten it to the door. It preferably makes an outward bend at d⁶, opposite the track-strip C, so as to avoid said strip, and from its inner side, at a point which is below the level of said strip when the hanger 60 is in place, one or more lugs d⁷ project inward far enough to strike the bottom of said track-strip when the hanger is lifted, as shown substantially in Fig. II. I prefer to use two lugs, as shown in Fig. IV; but the number is not 65 essential, as will be obvious.

On its outer side the hanger D contains a substantially T-shaped slot D⁴, whose head d⁸ is formed in the housing D' and whose body or tail d⁹ preferably extends down into the 75 arm D², substantially as shown. The inner side of the housing contains a T-shaped slot D⁵, whose head d¹⁰ is opposite the head d⁸ of the slot D⁴. It preferably differs from the slot D⁴ only in being shorter vertically and in 80 not having its lower end closed, as that of the slot D⁴ preferably is in practice. The lower end of the slot D⁵ passes between two lugs d¹¹, projecting downward from the inner side of the body of the housing and which are 85 preferably rounded on their outer edges d¹², as shown. The sheave D³ is preferably provided with trunnions d¹³, which when the sheave is in place turn in the heads of the slots D⁴ and D⁵, which act as bearings therefor. The space within the housing in which 90 the sheave D³ turns is preferably made but little wider than the sheave, so that when one of the sheave-trunnions breaks the adjoining inner side wall of the housing will retain the 95 sheave in a vertical position, and thus enable the sheave to continue to perform its function. In such cases the web c' of the track prevents the outward escape of the lug d¹¹ where the preferred form of track is used. Said space is also made narrow, preferably to 100 prevent the sheave from turning and getting off the track when both trunnions get broken. The length of the tail of the slot D⁴ is impor-

tant, because it enables the sheave to be inserted, notwithstanding the narrowness of the housing, where the housing and arm D² are formed integral, as they preferably are. The 5 distance from the tops or upper sides of the sheave-trunnions to the lower end of the slot d¹⁴ when the sheave is supporting the hanger and is directly over the vertical portion d¹⁴ of the slot D⁵ should be greater than the distance 10 from the lugs d⁷ to the under side of the track-strip C, so as to prevent the inside trunnion from escaping laterally when the hanger is lifted as high as the lugs d⁷ will permit, and I prefer that the distance from the axis 15 of the sheave to the lower end of the slot shall be slightly longer than the distance from the lugs d⁷ to the track-strip; but this, though desirable by reason of the greater security afforded and the avoidance of undue friction, 20 is not essential. On the other hand, the lugs d¹¹ should not be long enough to strike either the track C or the track-strip c when the sheave is performing its proper function. When, however, the sheave breaks and allows 25 the hanger to drop, it should be caught by the lugs d¹¹, which should then come to rest, preferably on the inside flange c' of the track C, and slide thereon, and said lugs, or at least one of them, should preferably, 30 when the hanger-sheave is on the track, normally extend below the level of the top of the upwardly-projecting portion of the track, so as to prevent the hanger from being accidentally drawn outward and disengaged from 35 the track when a sheave is broken. In the event of the breakage of the sheave-trunnions the rounded edges d¹² allow the lugs d¹¹ to serve as runners, and these lugs will then remove any deposit on the track that would 40 tend to impede the movement of the hanger therealong. Moreover, when these rounded edges d¹² are thus lowered into contact with the track they will engage and depress any projecting heads of the track-securing nails 45 or screws that may have gotten loose instead of catching said heads and pulling out the nails or screws, as would be the case with lugs having squared or angular edges. I prefer to use the form of hanger track-rail shown; 50 but any of the other well-known forms can be

substituted for it without departing from the substance of my invention. In the preferred form of my hanger-housing the lugs d¹¹ are the parts projecting down so as to prevent the escape of the hanger in case of the breakage of a sheave; but any other downwardly-extending portion of the hanger adapted to hook around the rail and support the hanger when a sheave is broken will answer the same purpose and would be the equivalent of the lugs d¹¹. 55

The periphery of the sheave D³ preferably contains an annular slot d¹⁵, adapted to receive the web c' of the track C when the form of track shown is used; but any of the well-known forms of sheave may be substituted for it. 60

The horizontal slots d⁸ d¹⁰ lie within the plane of the sides of the housing and open therethrough, so that the travel of the roller 70 or sheave trunnions will free the slots of any foreign matter. The slots terminate short of the ends of the housing, so that no retaining-lugs are necessary, with their accompanying liability of breaking and allowing the sheave 75 to escape. In fact, should the trunnions break the closed ends of the housing would prevent escape of the sheave.

I claim—

As an improved article of manufacture, a 80 car-door hanger comprising, a housing closed at its ends and formed with horizontal slots d⁸ d¹⁰ extending through its sides and terminating short of its ends, an attaching-arm depending from one side of the housing and 85 having a vertical slot d⁹ opening at its upper end into the middle of the slot d⁸, lugs d¹¹ depending from the opposite side of the housing and having rounded lower ends to serve 90 as runners upon the breaking of the sheave-trunnions; the lugs being spaced apart by a vertical slot d¹⁴ opening at its upper end into the middle of the slot d¹⁰ and a traveling sheave within the housing with its trunnions in the slots d⁸, d¹⁰; substantially as described. 95

LOUIS A. HOERR.
